ELECTRICAL CONNECTOR PLUG WITH RETRACTABLE PIN SHIELD

John P. Kostich, deceased, late of Ontario, Calif., by
Helen S. Kostich, administratrix, Ontario, Calif., as-
signor to Northrop Corporation, Beverly Hills, Calif.,
a corporation of California

Filed May 14, 1962, Ser. No. 70,105

Term of patent 14 years

(Cl. D26—1)

FIG. 1 is a frontal elevational view of an electrical connector plug with retractable pin shield, showing the new design;

FIG. 2 is a rear elevational view;

FIG. 3 is a bottom plan view;

FIG. 4 is a top plan view;

FIG. 5 is a right side elevational view;

FIG. 6 is a left side elevational view; and

FIG. 7 is a front, side and bottom perspective view thereof.

The dominant features of the design are shown in solid lines in the drawing.

What is claimed is:

The ornamental design for an electrical connector plug with retractable pin shield, substantially as shown and described.
